SHIELDED SPARK PLUG

Hector Rabezzana, Flint, Mich., assignor to General Motors Corporation, Detroit, Mich., a corporation of Delaware

Application December 27, 1938, Serial No. 247,741

4 Claims. (Cl. 123—169)

My invention relates to shielding means for spark plugs used with internal combustion engines to ignite the combustible mixture supplied to the engine cylinder and the object thereof is to provide a hollow metallic shield, or "can" as it is sometimes called, associated with an internal combustion engine cylinder and which encloses and serves as a protector for a spark plug of known and more or less conventional form; in combination with a readily attachable and removable cap for closing the open end of the shield to thereby form a complete enclosure for a spark plug contained therein. The usual insulated current supply lead is secured to and carried by said cap, and the act of placing the cap upon and removing it from the shield establishes and interrupts a connection between the insulated conductor of the supply cable through which current is supplied thereto and the insulated electrode of the spark plug within said shield.

In the drawing wherein the preferred embodiment of my invention is illustrated:

Figure 1 is a view showing my improved spark plug shielding device in elevation.

Figure 2 is a view showing the metallic shield and the cap therefor upon a central vertical plane indicated by the line 2—2, Figure 1, a spark plug and a supply conductor being shown in elevation and

Figure 3 is a view showing various parts of the cap for closing the open upper end of the shield and for securing the supply cable thereto in perspective and separated from one another.

Referring now to the drawing, the numeral 5 designates a hollow metallic shield tubular in form and open at its upper end, and having a threaded extension 6 at its lower end adapted to screw into an interiorly threaded passage in an engine cylinder, and which part 6 has a threaded passage adapted to receive a spark plug 7 of known and conventional form; and which shield extends upwardly and encloses the plug 7 throughout substantially the entire length thereof. The lower part of the shield therefore, in the form of shield shown, forms in effect a bushing for the spark plug; and the upper end thereof has a circumferentially extending groove 8 for receiving the lower ends of resilient holding members associated with the detachable cap aforesaid. The upper end of the shield is tapered as shown at 9 so as to facilitate the placing of the cap upon the upper end thereof, as will be understood; and an intermediate hexagonal part 10 is provided to receive a wrench for screw-

ing the shield into the threaded opening referred to in an engine cylinder.

The numeral 11 designates an insulating member made of a ceramic material, Bakelite, or equivalent substance and which has an annular depending skirt part 12 within the shield 5 which surrounds the upper end of the plug 7; that is, surrounds the upper end 13 of the insulated electrode and the upper part of the insulating member of the plug; and the dome-shaped upper part 15 of the insulating member 11 has a thin metallic shell member 16 of like form which overlies the dome-like part and is secured in place thereupon by lugs 17 which are bent inward so as to engage and lie beneath a circumferentially extending ledge 18 of the insulating member. Said member has an annular groove 19 just within the shoulder 18 which receives the upper end of the shield 5 when the cap which comprises the insulating member 11 and its dome-shaped shell member 16 is in place upon the shield; and said cap is held in place by resilient clips 20 depending from the shell member 16 and which are arranged in alternation with the lugs 17 as shown, and the lower ends of which lie within the groove 19 when the cap is in place closing the upper end of the shield. The presence of the tapered portion 9 and the fact that the holding clips 20 are resilient permits the closing cap member to be readily placed upon and removed from the shield member 5 as will be understood.

The insulating member 11 has a projecting tubular part or nipple 21 through which the supply cable 22 enters the shielding device, so that the insulated conducting wire 23 thereof will come into contact with the upper end 13 of the insulated electrode so as to supply current thereto, the axis of said nipple being inclined relative to the axis of the shield 5 so that the supply cable will be disposed at an angle to the axis of the spark plug, as shown; and the numeral 24 designates a knurled tubular securing member which surrounds the nipple 21, and has an inwardly extending ledge 25 which overlies a packing gasket 26 and compresses it against the end 27 of said nipple to secure the supply cable 22 to the cap and to provide a tight joint between the same and the cap. The insulating sheath of the supply cable may have a circumferential groove 28 into which the gasket 26 is compressed to provide a stronger connection between the parts if friction alone is deemed inadequate to secure a sufficiently strong connection between them.

The tubular securing member 24 is angularly rotatable about the supply cable 22 and has a

series of inclined lugs 28 adapted to engage and interlock with stationary lugs 29 carried by an annular member 30, which is secured to the shell member, 16 and surrounds an opening 31 in the wall thereof.

The supply cable 22 may therefore be secured to the cap by moving the tubular member 24 to bring the lugs 28 into positions adjacent the lugs 29, the gasket 26 being meanwhile compressed against the insulating covering of the cable, and then rotating the member 24 to bring the lugs 28 and 29 into interlocking engagement with one another.

The supply cable may obviously be disconnected from the cap without removing the cap from the tubular shield 5 by reversing the connecting steps above outlined. Ordinarily, however, the supply cable after having been secured to the cap will remain connected therewith; and the cap as a whole, and the supply cable with it, will be lifted from the tubular shield if and when the supply cable has to be disconnected from the spark plug or when access has to be had to the spark plug which is housed within the tubular shield.

Having thus described and explained my invention, I claim and desire to secure by Letters Patent:

1. Spark plug shielding means comprising a hollow metallic shield tubular in form and open at its upper end, and having a circumferentially extending groove located adjacent said upper end; an insulating member supported upon the upper end of said shield and having a depending annular skirt part which surrounds the upper end of a spark plug within said shield, and the upper end of which member has a tubular nipple arranged at an angle to the axis of said shield; and a metallic shell member overlying the upper end of said insulating member and secured in place thereupon by lugs of said shell which are bent into engagement with said insulating member, and which shell member has also resilient lugs depending therefrom and lower ends of which engage within the groove aforesaid of said shield.

2. Spark plug shielding means comprising a hollow metallic shield tubular in form and open at its upper end; an insulating member supported upon the upper end of said shield and having a depending annular skirt part which surrounds the upper end of a spark plug within said shield, and the upper end of which member has a tubular nipple arranged at an angle to the axis of said shield; a metallic shell member overlying the upper end of said insulating member and secured in place thereupon by lugs of said shell which are bent so as to lie beneath a circumferentially extending ledge upon the periphery of said insulating member, and which shell member has also resilient lugs depending

therefrom and the lower ends of which engage the periphery of said shield adjacent the upper end thereof; an angularly rotatable tubular member surrounding said nipple and having an inwardly extending ledge at its outer end, and a series of lugs at its inner end; and a series of lugs spaced about an opening in the wall of said shell member and with which said first mentioned lugs interlock when said tubular member is rotated.

3. Spark plug shielding means comprising a hollow metallic shield tubular in form and open at its upper end, and having a circumferentially extending groove located adjacent said upper end; an insulating member supported upon the upper end of said shield and having a depending annular skirt part which surrounds the upper end of a spark plug within said shield, and the upper end of which member has a tubular nipple arranged at an angle to the axis of said shield; a metallic shell member overlying the upper end of said insulating member and secured in place thereupon by lugs of said shell which are bent into engagement with said insulating member, and which shell member has also resilient lugs depending therefrom and lower ends of which engage within the groove aforesaid of said shield; an angularly rotatable tubular member surrounding said nipple and having an inwardly extending ledge at its outer end, and a series of lugs at its inner end; a gasket between said ledge and the outer end of said nipple; an annular member secured to said shell member and extending about an opening in the wall thereof; and a series of lugs carried by said annular member and with which said first mentioned lugs interlock when said tubular member is rotated.

4. Spark plug shielding means comprising a hollow metallic shield tubular in form and open at its upper end; an insulating member supported upon the upper end of said shield and having a depending annular skirt part which surrounds the upper end of a spark plug within said shield, and the upper end of which member has a tubular nipple arranged at an angle to the axis of said shield; a metallic shell member overlying the upper end of said insulating member and secured in place thereupon by lugs of said shell which are bent into engagement with said insulating member, and which shell member has also resilient lugs depending therefrom and the lower ends of which engage the periphery of said shell adjacent the upper end thereof; and separable connecting means associated with said shell member for securing a supply cable in place within said tubular nipple and for permitting said supply cable to be removed from said nipple.
